UNITED STATES PATENT OFFICE.

EUGENE DROUILLY, OF PARIS, FRANCE.

COMPOUND VESSEL.

No. 928,033.

Specification of Letters Patent.

Patented July 13, 1909.

Application filed May 13, 1908. Serial No. 432,693.

To all whom it may concern:

Be it known that I, EUGENE DROUILLY, a citizen of France, residing at Paris, France, have invented certain new and useful Improvements in Compound Vessels, of which the following is a specification.

My invention relates to improvements in compound vessels, and it consists in the constructions, combinations and arrangements herein described and claimed.

An object of my invention is to provide a compact and durable compound vessel for separately containing independent ingredients, or substances.

A further object of my invention is to provide an improved compound vessel, in which the several independent receptacles will be securely maintained sealed, and in which the closures of said receptacle will be efficiently shielded against accidental displacement.

A further object of my invention is to provide an improved compound vessel, in which the several closures of the independent receptacles will be positioned on the exterior of the vessel; thereby enabling each receptacle to be opened independently, and preventing the contents of any receptacle from coming in contact with the closures of other receptacles.

In the accompanying drawings forming a part of this application and in which similar reference symbols indicate corresponding parts in the several views—Figure 1 is a central vertical section illustrating one embodiment of my invention; and Fig. 2 is a central vertical section illustrating a modified construction.

Referring especially to Fig. 1 of the drawings, 1 indicates a main receptacle, which is preferably cylindrical and formed of any suitable material, such as tin or sheet metal. For convenience in packing and storing, the receptacle is provided with a flat bottom 2 and top 3. The flat top 3 is provided with a central opening, from the periphery of which a threaded cylindrical flange 4 extends within the receptacle. The cylindrical flange 4 braces the flat top 3 along the periphery of the central opening therein, and provides great strength and rigidity to said flat top. It will be noted that the flange 4 is supported only at its upper end, from which it extends freely within the receptacle; thereby permitting sufficient yielding of said flange to accommodate any irregularities, or slight distortions, occurring in the threaded per-

iphery 5 of the cylindrical cap engaging said flange.

The cylindrical cap has an open top, from which an annular flange 6 extends radially for engaging the flat top 3 of the receptacle to securely seal the latter. The engagement of the flange 6 with the top of the receptacle produces a frictional resistance tending to prevent accidental loosening of the cap. Further, the flange 6 lies snugly against the flat top 3 in a position which efficiently shields it from being accidentally struck or displaced. The annular flange 6 is provided with notches 7 to provide convenient means for engaging said flange in screwing the cap to position. An auxiliary receptacle 8 extends from the flat base 9 of the cap, and is provided with suitable securing means, such as threads 10 at its upper portion. An auxiliary cap is provided with a threaded portion 11 for engaging the threads 10, and with an annular flange 12 extending radially for engagement with the flat base 9 to securely seal the auxiliary receptacle. The flange 12 carries an axially extending flange 13, provided with notches 14 for convenient engagement in screwing the auxiliary cap to position.

From the above description it will be understood that my invention provides an improved construction in which the several independent receptacles of a compound vessel will be securely maintained sealed, and in which the closures of said several receptacles will be located exterior of the vessel and efficiently shielded against accidental displacement.

Fig. 2 illustrates a modified construction, comprising a main receptacle 15 provided with a flat top 16 having a central opening surrounded by a beading 17. An auxiliary receptacle 18 is provided with an annular flange 19 against which is seated a suitable packing ring 20 for engagement with the beading 17. A cap closure 21 threadingly engages the main receptacle at 22, and is provided with a central convex portion 23 for engaging the top edge of the auxiliary receptacle 18 to securely close the latter. When the cap closure 21 is screwed tightly in position, the convex portion 23 thereof will be forced against the top edge of the auxiliary receptacle; thereby securely closing said receptacle and pressing the packing ring 20 firmly against the beading 17 to seal the main receptacle 15. This provides a very simple

and durable form of compound vessel, capable of containing separately independent substances.

My invention is adapted for use in all cases where it is desired to maintain different substances distinctly separated. It is especially adapted for convenient use as an artist's box, where it is frequently desirable to carry the dry colors and varnish separately, in order that they may be mixed in the proper proportion when required for use.

I have illustrated and described a preferred and satisfactory construction, but, obviously, changes could be made within the spirit and scope of my invention.

Having thus described my invention, what I desire to secure by Letters Patent is:—

In a compound vessel, the combination of a main receptacle provided with a flat top

and a threaded cylindrical flange extending inwardly therefrom, a screw cap fitting within said threaded flange and provided with an annular base and an external flange for frictionally engaging the top of said main receptacle, an auxiliary receptacle dependent from the annular base of said cap, and a screw closure for said auxiliary receptacle provided with an external flange for engaging the base of said cap and a notched rim extending upwardly from said flange of less length than 30 said cap, substantially as described.

In testimony whereof I affix my signature in presence of two witnesses.

EUGENE DROUILLY.
